UNITED STATES PATENT OFFICE.

EDMUND HUGH PRYCE, OF NEW YORK, N. Y.

FLYING-MACHINE.

1,258,943.

Specification of Letters Patent. Patented Mar. 12, 1918.

Application filed December 15, 1911, Serial No. 665,906. Renewed July 30, 1917. Serial No. 183,638.

To all whom it may concern:

Be it known that I, EDMUND HUGH PRYCE, a subject of the King of Great Britain, and a resident of New York city, in the county 5 of New York and State of New York, have invented certain new and useful Improvements in Flying-Machines, of which the following is a specification.

My invention relates to flying machines 10 and the object of my invention is to provide a flying machine which will be stable in flight, simple in construction and of great strength. Further objects and advantages of my new construction will be set forth in 15 the following description of my invention and the features of novelty pointed out in the claims hereinafter presented.

Referring to the drawings,

Figure 1 is a side view of my improved 20 machine which travels in the direction indicated by the arrow.

Fig. 2 is a longitudinal sectional view of the machine.

Fig. 3 is a cross sectional view of line 3—3 25 of Fig. 2.

Fig. 4 is a front view of the machine.

A and A' indicate end frame elements of 30 the machine, and are formed like wheels, the spokes being indicated by a, a, a, etc., and the hubs A²—A² being provided with 35 grooves A³—A³ respectively. The frame is constructed to rotate on a central tubular element B, which carries bearing elements C—C respectively, ball bearings C' being shown in these drawings, but it is obvious 40 that any proper form of bearing may be used.

A motor D is suspended from the tube B by metal or other suitable stiff hangers 45 D'—D', the ring portions D²—D² being fastened rigidly to the tube B. The bottom of the tube B is slotted as indicated at B' to permit the chain E, driven by the motor, to drive the shaft F which extends longitudinally through the tube B, and is supported 50 at each end by bearings G and G' respectively, which bearings are held rigidly in the tube B, and preferably in vertical alignment with the bearing elements C.

55 A propeller H is mounted on the shaft F. To further support the shaft F and propeller H, a separate bearing I is provided which is located just behind the propeller and is provided with an annular groove I' in

which the forward end of the tube B fits. 55 Two bifurcated depending rods J—J respectively are connected with the tube B either directly or indirectly and extend below the frame elements A and A' to the truck portion, which portion comprises the wheels 60 K—K—K, etc., and a seat L for the aviator, and carries the usual levers and control devices necessary to govern the machine in its flight.

M, indicates a rod which extends from the 65 rear end of the tube B and N indicates one of the steering planes which is hinged at N' to permit the plane N to be swung laterally, and N² is a steering plane supported by the plane N and extending horizontally and at 70 right angles to plane N and may be turned on its axis N³ by the cord N⁴ to govern the rise and fall movement of the machine.

A cord or chain O passes over a wheel O' which is fastened to the shaft of the plane 75 N, and extends around a wheel P which is operated by means of the hand wheel Q, and thus the plane N may be swung on the hinge N'. Other suitable means may be employed to control the steering planes N and N², this 80 being a matter of minor importance.

Springs R—R—R respectively are used between the upper frame portion J and J' and the wheels K to prevent shock when the machine comes in contact with the ground in 85 alighting. Rods S—S respectively are connected to the tube B and guy wires S'—S' respectively extend from them to the shaft M to support the same as indicated. The frame elements A and A' are each provided 90 near their periphery with bearings T—T, etc., which are spaced apart from each other circumferentially, and tubular shafts V—V, etc., are fitted to turn therein and extend across from the frame portion A to portion 95 A', and suitable collars T' are connected to shafts T to hold said shafts in position.

A rod W extends entirely through each shaft V and is free to turn relative thereto. Wide, continuous bands X—X respectively 100 are passed over the extended ends of the rods W and are held thereon by collars W', and said bands serve as planes to help support the machine in the air. They may be made as wide as required. Fastened rigidly to each shaft V, is a supporting plane Y which is held to said shaft by supports Y'—Y', etc., substantially as illustrated.

Y^2 — Y^2 , etc., respectively indicate further supporting plane surfaces which are properly held in position by any suitable well known means.

5 On one end of each shaft V is mounted a sprocket wheel Z and on the tube B adjacent to the ends thereof are sprocket wheels Z' and Z^2 respectively. The sprocket wheels Z which are located directly opposite to each other on the frame portions A and A' are connected together by chains b when the planes Y extend parallel with each other, the planes being set in position to extend horizontally as illustrated in Fig. 4. On the 10 spokes a are mounted cross pieces d which are bifurcated at each end and in said ends tension pulleys e are held against which the chains b press to hold the chains in proper 15 adjusted position on to the sprocket wheels Z and Z' as will be readily understood.

20 An opening f is formed in the forward end of the tube B on the underside, through which electrical conductors can be passed longitudinally through the tube B and down 25 through the opening B' to the motor D to control the spark which ignites the gases in the motor. It is obvious that if a steam motor or other type of motor were used, that the means for controlling the same could be 30 passed through the openings f and B' , so that it could be started or stopped from the aviator's position located at the seat L .

The machine is operated as follows:—

35 The engine cylinders are charged with gas under compression and the aviator then closes the electric circuit through the spark plug to ignite said gases thus starting the motor which drives the shaft F and propeller H through the instrumentality of the 40 drive chain E . The propeller acting on the air drives the machine forward in the direction indicated by the arrow in Fig. 1, until the machine has obtained sufficient velocity for the air acting on the under side of the 45 plane surface Y and the plane bands X to lift the machine from the ground after which the rise and fall of the machine is governed by the steering plane N^2 and the turning movements by the plane N by means 50 of the hand wheels and the control cords N^4 and O respectively, as will be readily understood.

55 In case a gust of wind should impinge against the planes on one side of the machine, tending to lift the planes on the right-hand side of the machine for illustration, the whole frame comprising the elements A , A' and the shafts V would revolve about the tube B and at the same time rotate in the 60 bearings T , while the planes Y would be kept in a horizontal position by means of the chains b , due to the fact that the sprocket chains b engage with the sprockets Z' and Z^2 which are mounted on the tube B in fixed 65 relation therewith, and, therefore, as the

frame elements A and A' revolve about the tube B , the chains b will act to turn the shafts V in proportion to the distance the frame elements A and A' revolve, thus keeping the planes Y in proper horizontal position. 70

By reason of the truck and weight of the motor being connected and fixed directly to the tube B and suspended therefrom, they serve as a lever to prevent the wind acting 75 on the vanes from rotating the tube B , and, therefore, the effort of the motor in turning the shaft F is counteracted, as will be readily understood. The rods W are free to turn in the shafts V , and, therefore, offer no resistance to the turning of the said shafts 80 in the bearings T . The webs X could be supported on shafts fixed directly to the frame portions A and A' respectively, instead of to the rods W if desired, without 85 changing the operation or action of the said plane surfaces, as will be readily understood by any person skilled in this art.

Having thus described my invention, I claim as new:—

90 1. In a flying machine, a central relatively stationary element, a frame mounted on said element and rotatable relative thereto, shafts carried by said frame and rotatable therein, supporting planes carried by said shafts to 95 sustain the machine by the sustaining action of the air exerted through the rapid forward motion of the machine, means for automatically controlling the rotation of said shafts through the rotation of the frame 100 relatively to the stationary element to maintain the planes in proper position to sustain the machine, and means for propelling said machine.

105 2. A machine comprising a central tubular element, a frame mounted on said tubular element and rotatable relative thereto, shafts carried by said frame and rotatable therein, supporting planes carried by said shafts, means for controlling the rotation of said 110 shafts, rods extending from the sides of said frame, a band supported by said rods presenting plane surfaces, and means for propelling said machine.

115 3. A machine comprising a central tubular element, a frame mounted on said tubular element and rotatable relative thereto, shafts carried by said frame and rotatable therein, supporting planes carried by said shafts, means for controlling the rotation of said 120 shafts, rods extending from the sides of said frame, a band at each end of said machine supported by said rods, and means for propelling said machine.

125 4. A machine comprising a central tubular element, a frame mounted on said tubular element and rotatable relative thereto, shafts carried by said frame and rotatable therein, a plurality of supporting planes carried by each of said shafts, means for controlling 130

- the rotation of said shafts, rods extending from the sides of said frame, a band at each end of said machine supported by said rods, and means for propelling said machine.
- 5 5. A machine comprising a central tubular element, bearings located in said element, a shaft supported in said bearings, a propeller mounted on one end of said shaft, a motor suspended from said tubular element, a driving means connecting said motor with said shaft, a frame mounted on said tubular element and rotatable relative thereto, shafts carried by said frame and rotatable therein, supporting planes carried by said shafts, and
- 10 15 means for rotating said shafts as the frame turns relative to the said tubular element.
6. A machine comprising a central bearing element, a frame mounted thereon and rotatable relative thereto, plane surfaces carried by said frame, means for maintaining said plane surfaces in horizontal position as the frame rotates relative to said central bearing element by reason of gusts of wind striking said planes, a structure adapted to carry an aviator fixedly connected to said central bearing element and suspended beneath said frame, a propeller and means comprising a motor for driving said machine.
- 20 25 30 35 40 45 50 55 60 65 70 75 80 85 90 95 100 105 110 115 120 125 130
7. A machine comprising a central bearing element, a frame mounted thereon and rotatable relative thereto, plane surfaces carried by said frame, means for maintaining said plane surfaces in horizontal position as the frame rotates relative to said central bearing element by reason of inequalities in inward pressure, a structure adapted to carry an aviator fixedly connected to said central bearing element and suspended beneath said frame, means comprising a motor and a propeller for driving said machine, and means supported by said central bearing element for steering said machine in flight.
8. A machine comprising a central tubular element, a frame mounted on said tubular element and rotatable relative thereto, shafts carried by said frame and rotatable therein, supporting planes carried by said shafts, means for controlling the rotation of said shafts when the planes are moved by inequalities in wind pressure, means for propelling said machine, and means supported by said central bearing element for steering said machine in flight.
9. A machine comprising a central tubular element, a frame mounted on said tubular element and rotatable relative thereto, shafts carried by said frame and rotatable therein, supporting planes carried by said shafts, means for controlling the rotation of said shafts, rods extending from the sides of said frame, a band supported by said rods presenting plane surfaces, means for propelling said machine, and means supported by said
- central bearing element for steering said machine in flight.
10. In a flying machine, a relatively stationary frame, a plurality of supporting planes, mounted so as to swing about said frame in response to gusts of wind, propelling means independent of said planes, and means for automatically maintaining said planes horizontal during their swinging movement.
11. In a flying machine, a relatively stationary frame, a movable frame, mounted so as to swing on said first mentioned frame about an axis corresponding to the direction of flight, a plurality of supporting planes mounted on said frame, said movable frame being adapted to be swung about its axis by any inequality of pressure exerted by gusts of wind upon the supporting planes, and means for keeping said supporting planes horizontal in all positions.
12. In a flying machine, propelling means, a relatively stationary frame, a frame movably mounted on said relatively stationary frame, supporting planes independent of the propelling means mounted on said movable frame to sustain the machine through sustaining forces arising through the rapid forward movement of the machine, and a controlling connection between said stationary frame and planes whereby said planes are kept substantially horizontal in any position of the movable frame.
13. In a flying machine, propelling means, a relatively stationary frame, a second frame mounted thereon, and movable thereon about an axis corresponding to the direction of flight, a plurality of supporting planes mounted upon said movable frame, said supporting planes being independent of the propelling means and serving to sustain the machine through the sustaining action of the air exerted through the rapid forward motion of the machine, a stationary member mounted upon said stationary frame, and controlling connections between said stationary member and said supporting planes adapted to automatically maintain said supporting planes horizontal in any position of the movable frame.
14. In an aeroplane, a body, a frame pivoted to the body and free to move relatively thereto under the influence of the wind, a plurality of supporting plane members pivoted to the frame, and means for rotating the plane members relatively to the frame on the rotation of the frame.
15. In an aeroplane, a main frame, a second frame pivoted thereto and free to move relatively to the frame under the influence of the wind, four supporting plane members spaced at equal distances apart and pivoted to the second frame intermediate the sides, and at equal distances from the axis of the second frame and means to rotate

the plane members relatively to the second frame on the rotation of the second frame relatively to the first frame.

16. In an aeroplane, a main frame, a second frame pivoted to the main frame and free to move relatively to the main frame under the influence of the wind, a plurality of supporting plane members spaced at equal distances apart and pivoted to the second frame intermediate the sides at an equal distance from the axis of the second frame, a hub on the second frame, hubs on the plane mem- 10

bers, and means for rotating the hubs for rotating the plane members simultaneously on the rotation of the second frame relatively to the first frame.

Signed at New York city in the county of New York and State of New York this 1st day of December, A. D. 1911.

EDMUND HUGH PRYCE.
